UNITED STATES PATENT OFFICE.

GEORGE B. WOOD, OF DETROIT, MICHIGAN.

TIRE-TUBE-REPAIRING KIT.

Application filed November 9, 1918. Serial No. 261,795.

To all whom it may concern:

Be it known that I, GEORGE B. Wood, a citizen of the United States, and residing at Detroit, in the county of Wayne and State 5 of Michigan, have invented a new and Improved Tire-Tube-Repairing Kit, of which the following is a specification.

The present invention relates to a kit for repairing tire tubes and is an improvement 10 on that disclosed and claimed in my U. S. Letters Patent No. 1,281,469, granted October 15, 1918.

In the use of such kits, it is necessary that the soapstone or other foreign matter 15 which ordinarily clings to the surface of the tire be removed around the cut or tear in order to secure a fresh and clean rubber area for the application of the cement. This may be done by the use of a rag wet in gaso- 20 line, but the clothing of the user is often soiled thereby, and the operation is otherwise unsatisfactory. Moreover, the wet rag is usually either thrown away after using 25 or inserted in the can, the net result being that the rag is either often missing when most needed or is pressed against the inner container and tends to soak off the abrasive with which one end of the latter is prefer- 30 ably covered.

In accordance with the present invention, the can cover is provided on its inner face with a pad of compressed felt or the like 35 which may be used, when the cover is taken off and firmly grasped in the hand after the pad has been saturated, as an effective im- 40 plement for rubbing and cleaning the rubber. The cover itself is preferably of tin and presents a relatively sharp edge with which the rubber may be further worked upon or scraped to expose fresh rubber surfaces and to remove foreign matter.

The invention is also concerned with an improved assembly of the inner container and the clamp within the can, whereby the 45 former is kept away from the pad.

Again, the invention consists in certain improvements in the clamp whereby a more uniform gripping of the tire is attained.

In the drawing, Fig. 1 is a central longitudinal section showing one embodiment of 50 the invention. Fig. 2 is a perspective view showing the manner of holding and working on the tire. Figs. 3 and 4 are perspective views of the clamp and the inner container respectively. Fig. 5 is an end view of the clamp.

The kit or package as sold includes an outer container 1 and an inner container 2 both preferably being cylindrical paper cans. These cans have covers 3 and 4, respectively, the former being of tin or the like and preferably of the screw threaded type. There is considerable difference in the diameter of the cans, which provides space for a clamp 5. Within the inner container is a roll of patch material 8 and a can 60 of cement 9. One end of the can 2 is preferably coated with glue and dipped into emery dust to form an abrasive outer surface 10.

Various forms of clamps may be used but I prefer that shown, which is formed from a single piece of spring wire bent to form two gripping portions or jaws 12 and 13 joined by a loop 14 whereby they are nor- 70 mally held apart from each other. The gripping portions are of a length exceeding the diameter of the tire tubes, and the portion 12 is offset near its end to form a keeper or seat 15 into which the end of the portion 13 is received when the clamp is closed.

This clamp differs from that shown in my patent above referred to substantially only in that the loop 14 is in this instance bent 75 into a plane at an angle to the plane determined by the jaws. The change is of great practical importance, however, as a much more uniform gripping of the tire and a much greater ease of manipulation is thus 80 secured; in other words, the previous clamp was relatively stiff and exhibited a tendency to grip the tire with a considerably greater pressure at the points where the jaws merge into the loop 14 than elsewhere, which was 85 due to the fact that the jaws necessarily flexed about the mid-point of the loop, whereas in the present case the jaws may be 90 said to flex or have angular movement relative to one another about an imaginary 95 point in their own plane beyond the mid-point of the loop.

Attached to the cover 3 on the inner side 100 thereof in any suitable manner, as by means of a screw 17 or a coating of shellac, is a 105 pad or swab 18, preferably formed of compressed felt.

When a cut or blow out is to be repaired, the contents of the outer container are removed and the tire is clamped in looped 110 form about the latter, as shown in Fig. 2, the cut appearing at 19. The cover 3 is then

turned upside down and sufficient gasoline or the like poured into it to wet the swab, after which the tire is rubbed with the latter end and scraped with the edge of the metal cover, if necessary, in the general manner indicated. Finally the rubber may be roughened or dressed with the abrasive 10, and a patch applied as described in my above identified patent.

- 10 By assembling the kit so that the offset end of the jaw 12 comes between the pad and the inner container, the latter is kept free from the injurious effects the gasoline might otherwise have thereon.
- 15 Various changes other than those indicated may obviously be made without departing from the spirit of my invention; I

do not, therefore, wish to be limited except as indicated by the subjoined claim.

I claim:

20 A tire tube repairing kit comprising an outer cylindrical container having a detachable cover, a pad of fibrous material secured to the cover on the inner side thereof, a second cylindrical container within the first 25 and adapted to contain tire patches, a clamp for securing a tire tube looped about the outer container, said clamp being adapted to be inserted in the outer container and having a portion arranged to extend between 30 the pad and the inner container to space the latter from the former.

GEORGE B. WOOD.
